UNITED STATES PATENT OFFICE.

REUBEN H. BARE, OF ORCUTT, CALIFORNIA, ASSIGNOR OF ONE-HALF TO
HARRY H. LEWIS, OF LOS ANGELES, CALIFORNIA.

OIL-WELL CLEANER.

No. 845,677.

Specification of Letters Patent.

Patented Feb. 26, 1907.

Application filed February 13, 1906. Serial No. 300,905.

To all whom it may concern:

Be it known that I, REUBEN H. BARE, a citizen of the United States of America, residing at Orcutt, in the county of Santa Barbara and State of California, have invented new and useful Improvements in Oil-Well Cleaners, of which the following is a specification.

This invention relates to a device for cleaning the lining tubes or casings of oil-wells to 10 secure the free and unrestricted flow of oil thereto from the bearing strata.

As is well known, the bores of oil-wells are lined by tubular casings extending from top to bottom thereof, the bottom of each casing 15 being suitably closed and perforations provided in the wall of the casing to permit the oil to flow therein. With the inflowing oil sand, grit, and other particles pass into the casing, and in course of time the perforations 20 or inlets become clogged by the accumulation of foreign matter therein, thus restricting the flow of oil and capacity of the well.

The object of the present invention is to provide a simple and effective construction 25 of device whereby the perforations of the casing may be quickly and conveniently freed from the foreign particles collected therein when they become clogged.

In the accompanying drawings, Figure 1 is 30 a vertical longitudinal section of the lower portion of a well-tube, showing the cleaning device inserted therein and illustrated as nearing the limit of its downstroke. Fig. 2 is a view similar to Fig. 1, representing the 35 cleaning device in the preliminary movement of its upstroke.

Referring now more particularly to the drawings, the numeral 1 represents an oil-well tube or lining provided at its lower end 40 with a suitable closure 2 and formed with rows of apertures or perforations 3, through which the oil from the boring rock or sand flows into said tube. The oil is pumped to the surface in a manner well understood by 45 those versed in the art; but in course of time the perforations 3 become clogged by sand, paraffin, and other deposits, and the capacity of the well is correspondingly decreased.

In carrying my invention into practice I 50 provide a plunger composed of a hollow or tubular body portion 4 open at each end and provided adjacent its upper end with a seat 6 for an upwardly-movable hinged flap-valve 7. The upper and lower ends of the body are

externally threaded, as indicated at 8 and 9, 55 respectively, and surrounding the same between said threaded portions is a packing-sleeve 10, made of rubber, canvas, or of a composite material. This sleeve or gasket increases the diameter of the plunger-body to 60 a proper extent to snugly conform to the internal diameter of the well-tube 1. The sleeve is retained in position by upper and lower adjusting collars or nuts 11 and 12 engaging the threaded portions 8 and 9, and 65 engaging the latter-named threaded portion is also a threaded collar or nut 13, which acts as a lock-nut to hold the collar or nut 12 against retrograde rotation. By adjusting the collars or nuts 11 and 12 the washers 70 composing the gasket or packing-sleeve may be adjusted to fit snugly together to prevent the passage of oil therebetween and held firmly in such adjusted position. The plunger is provided at its upper end with a head 14 of 75 reduced diameter with respect thereto and to the well-tube 1 and formed with vertical longitudinal ports or passages 15, adapted to communicate with the tube above the body of the plunger and with the interior of the 80 tubular body. The lower end of the head is threaded, as indicated at 16, for engagement with the upper extremity of the threaded portion 8 and serves as a lock-nut to hold the collar or nut 11 from movement. The head 85 also has a reduced threaded upper end 17 for coupling engagement with the working barrel or tubing, as shown at 18.

In operation the device is inserted into the well and coupled to the working barrel or 90 tubing, so as to be reciprocated when the tubing is pulled from the well and replaced. On the downward movement of the tubing the oil contained in the lower portion of the casing will flow up into the tubular body 4 95 and automatically close the valve 7, which will prevent the oil from flowing into the casing above the plunger, and consequently as the tubing continues to descend the oil in advance thereof will be forcibly ejected below through the perforations or apertures 3 in the casing below the plunger, thus washing out the deposits. The oil displaced from the casing by the cleanser will be forced back into the bearing rock or strata, and a portion 100 of the same will enter the casing through the apertures 3 above the cleanser-body and will remain therein during the descent of the

tubing, owing to the fact that the valve 7 will be held by the pressure of oil below. Upon the upward movement of the tubing the valve 7 will open under pressure of the oil 5 above and the relief afforded below by the escape of the oil from the body-casing, and the oil contained in the casing above the cleanser will therefore flow, together with all the accompanying impurities, through 10 the ports 15 in the head 14 and thence down through the tube 4. The operation above described is repeated as long as necessary until the perforations 3 are clear and the normal production of the well restored.

15 I wish it to be understood that the body portion of the plunger 4 is provided at its upper end with a portion 5, constructed of a diameter smaller than the lower end of the plunger, and a surrounding shoulder 6' is 20 formed contiguous with the portion 5. Said portion and shoulder serves to form the

valve-seat 6 and prevents the oil from having an upward passage when said valve is in contact with said seat.

Having thus described the invention, what 25 is claimed as new is—

An oil-well cleaner comprising a plunger with a tubular body portion, a head arranged above the same, said body portion having at its upper end a portion 5 smaller in diameter than the lower end of the plunger, a surrounding shoulder contiguous with the portion 5 said portion and shoulder serving to form a valve-seat and a hinged valve adapted to close upwardly against said seat 30 as specified.

In testimony whereof I affix my signature in presence of two witnesses.

REUBEN H. BARE.
